UNITED STATES PATENT OFFICE

2,513,104

PEDESTAL-TYPE HYDRANT

Amos O. Payne, Cincinnati, Ohio, assignor to
OPW Corporation, Cincinnati, Ohio, a corpora-
tion of Ohio.

Application March 11, 1949, Serial No. 80,835

7 Claims. (Cl. 137—13)

1.

This invention relates to pedestal-type hydrants and more particularly to a hydrant enclosure of the non-freezing type adapted to be secured to the upper end of a pipe or housing which extends into the ground.

Sanitary water service hydrants or fixtures of the type used in servicing railroad cars and the like are commonly installed out of doors and are unattended in railroad yards where there is danger of pollution from various sources of unsanitary water, and an object of this invention is to provide a housing or enclosure for a pedestal-type hydrant which protects the hydrant and the spout of the hydrant from contamination by outside or surface water.

A further object of this invention is to provide a sanitary hydrant and an enclosure or housing for the hydrant which prevents freezing of water in the hydrant during cold periods.

A further object of this invention is to provide a hydrant housing and cover or closure for a hydrant spout and handle which covers and protects the hydrant spout and prevents water on the housing or enclosure from reaching the hydrant spout when the cover is closed.

A further object of this invention is to provide a cover or closure for a hydrant spout which automatically falls to closed position when a hose is uncoupled from the spout and which has flanges that cooperate with flanges on the hydrant enclosure to divert any water on the surface of the housing away from the hydrant spout.

Other objects and features of the invention will in part be apparent and will in part be obvious from the following detailed description taken in conjunction with the accompanying drawings, in which:

Figure 1 is a perspective view showing a hydrant enclosure constructed in accordance with an embodiment of this invention, a portion of the cover being broken away to reveal details of construction of the enclosure body;

Fig. 2 is a view in side elevation of the enclosure shown in Fig. 1, a portion of the cover and body being broken away and insulation being removed to reveal details of construction;

Fig. 3 is a top plan view, partly broken away and in section, of the enclosure, part of the insulation being removed; and

Fig. 4 is a fragmentary view showing the interior of the cover.

In the following detailed description and the drawings like reference characters indicate like parts.

As shown in Fig. 1, a vertical pipe or housing 10 supports a hollow hydrant enclosure body 12 of the non-freezing type which is secured to the upper end of housing 10. The pipe or housing

2.

10 extends downwardly into the ground or through a pavement to a depth below the frost line.

The enclosure body 12 is preferably cylindrical in its overall shape, and has a closed top 14. As shown in Fig. 2, enclosure body 12 is open at the bottom to accommodate a water supply line 16 and a water discharge line 17 which extend through the body and the pipe or housing 10 in spaced relation to the walls thereof. The front face or side of the enclosure body has a flat vertical section as indicated at 17.

Adjacent the top of body 12, an opening 18 is provided in the wall 17 thereof to accommodate a hydrant valve 19 and permit attachment of the valve to the enclosure body 12. The valve may be of the type described in detail in my copending application, Serial No. 75,937, filed February 11, 1949, to which reference may be made for further details of construction of the valve. The hydrant includes an operating handle 21 and a spout 22 which extend outwardly from the body of the enclosure. A body or base 23 of valve 19 extends into the enclosure body 12, and water may be slowly circulated through the valve body by any suitable means, as indicated by arrows in Fig. 2, to prevent freezing of water therein during cold weather.

A cover or closure, indicated generally at 24, is hinged to enclosure body 12. Cover 24 is hollow and when in closed position as shown in Fig. 2 shrouds the spout 22 and operating handle 21. Cover 24 can be swung upwardly to give access to the spout and handle. A stop 25 forms a part of the top 14 of the enclosure body and limits the extent to which cover 24 may be raised so that the cover at all times tends to fall to closed position.

The cover 24 is hollow and includes a top 26, sides 27 and a curved front panel or wall 28 to which a finger grip 29 is fixed. The cover is provided with a flange 31 along the free or outer edge of the top and side flanges 32 along the upper edges of the sides 27. Flanges 31 and 32 cooperate with and fit against front flange 33 and side flanges 34, respectively of the enclosure body 12 when the cover is in lowered or closed position so that if any water falls on the top of the enclosure body or on cover 24, such water can run off along flanges 33 without entering beneath cover 24 or escaping into or on spout 22. As shown in Figs. 1 and 2, flange 33 and the front portion of enclosure top 14 form a V-shaped notch which catches any water which may fall on the top of the enclosure body and diverts the water from the hydrant spout. The sides 27 of the cover fit closely about side flanges 35 of the

enclosure body to give protection along the sides of the enclosure body.

The cover is hinged on a pair of trunnions which are formed from studs 37 fixed to bosses 38 which form a part of the enclosure body 12 and extend outwardly on diametrically opposite sides of the body. The trunnion studs extend through bearings 39 in cover 24 and pivotally support the cover.

As shown in Fig. 2, the lower margin 40 of the cover 24 fits against the side flanges 35 when the cover is closed and limits the extent to which the cover can swing downwardly. As shown in Figs. 2 and 4, flanges 41 extend across the inside of side walls 27 of the cover from outer edges of the lower margin 40 and abut the flanges 35 when the cover is closed to divert any water which may splash against the sides of cover 24 from the hydrant spout 22. However, the central portion of the margin has no flange and any water which may penetrate inside the cover can flow away between the cover and flanges 35.

As shown in Figs. 1 and 3, the enclosure body 12 and the pipe or housing 10 may be filled with thermal-insulation 42 of any appropriate or suitable type, to prevent rapid chilling of water in the supply and discharge lines 16 and 17 and in the valve body 23. To facilitate placing of the insulation, an access opening 43 is provided in the enclosure body 13 opposite opening 18 through which insulation is inserted when packing the housing. The access opening 43 normally is closed by a plug 44 threaded therein, and additionally provides access to the hydrant during assembly, adjustment, or removal thereof.

When a hose is to be connected to hydrant spout 22, cover 24 is swung upwardly to permit access to the spout. As long as the hose is attached, the cover can rest on the hose, and the cover extends above face plate 17 forming a hood over the spout. The cover is hinged so that it can only be raised until flange 31 abuts the stop 25, and at all times the cover tends to fall closed. When closed, as shown in Fig. 2, cover flange 31 abuts enclosure body flange 33, and any water which may fall on the top of the enclosure body is diverted from the front face 17' and the hydrant spout to flow down enclosure body side flanges or shoulders 34 so that the hydrant spout at all times is effectively protected against contamination by outside or surface water.

The embodiment of the invention described above and illustrated in the drawings may be modified and changed in various structural details without departing either from the spirit or the scope of the invention as set forth in the appended claims.

Having described my invention, what I claim as new and novel and desire to secure by Letters Patent is:

1. A hydrant enclosure for a non-freezing pedestal-type hydrant which comprises a hollow enclosure body closed at the top and open at the bottom adapted to be secured to the upper end of a housing and adapted to accommodate a water supply line and a water return line in spaced relation to walls of the enclosure body, said enclosure body having an opening in a front wall adjacent the top to accommodate a hydrant valve attached thereto, said valve having a spout and operating handle extending outwardly of the enclosure body, and a valve body extending inside the enclosure body for attachment to the water supply and return lines, a hollow cover

for the spout and operating handle, pivot supports for said cover on opposite sides of the enclosure body, an outwardly extending flange on said enclosure body disposed about the opening for said hydrant, and a flange on said cover adapted to overlie and cooperate with the flange on said body when closed to divert surface water from the hydrant spout, said cover swinging about said pivot supports between an open position in which the spout and operating handle are exposed and a closed position in which the cover shrouds the spout and operating handle.

2. A hydrant enclosure for a non-freezing pedestal-type hydrant which comprises a hollow enclosure body closed at the top and open at the bottom adapted to be secured to the upper end of a housing and adapted to accommodate a water supply line and a water return line in spaced relation to the walls of said enclosure body, said enclosure body having an opening in a front wall adjacent the top to accommodate a hydrant valve attached thereto, said valve having a spout and an operating handle extending outwardly of the enclosure body and a valve body extending inside the enclosure body for attachment to the water supply and return lines, a hollow cover for the spout and operating handle, pivot supports for said cover on opposite sides of the enclosure body, outwardly extending side, top, and bottom flanges on said enclosure body disposed about the opening for said hydrant, said cover having side walls adapted to fit over the enclosure body side flanges when the cover is closed, a top flange on said cover adapted to overlie the top flange of the enclosure body when the cover is closed, a pair of sloping shoulders on said enclosure body extending backwardly and downwardly from the enclosure body top flange toward the pivot supports, and side flanges on the side walls of the cover adapted to overlie the shoulders on the enclosure body when the cover is closed, said cover swinging about said pivot support between an open position in which the spout and operating handle are exposed and a closed position in which the cover shrouds the spout and operating handle and the flanges provide an interlocking closure above the spout and operating handle.

3. A hydrant enclosure for a non-freezing pedestal-type hydrant which comprises a hollow hydrant enclosure body closed at the top and having an opening in a front wall adjacent the top to accommodate a hydrant valve attached thereto, side, top, and bottom flanges on said front wall about the opening, said hydrant valve having a spout and an operating handle extending outwardly of the enclosure body, a hollow cover for the spout and operating handle, pivot supports for said cover on opposite sides of the enclosure body, said cover having a top wall, a front wall, and a pair of side walls, a flange along said top wall and adapted to overlie the top flange of the enclosure body when the cover is closed, side walls of the cover being adapted to fit about the side flanges of the enclosure body when the cover is closed, a pair of shoulders on said enclosure body sloping downwardly and backwardly from the enclosure body top flange toward the pivot supports on opposite sides of the enclosure body, and flanges along top edges of the cover side walls adapted to overlie the shoulders when the cover is closed, said cover front wall having a lower margin adapted to abut the body bottom flange when the cover is closed, said cover swinging about said pivot supports between an open

position in which the spout and operating handle are exposed and a closed position in which the cover shrouds the spout and operating handle.

4. A hydrant enclosure for a non-freezing pedestal-type hydrant which comprises a hollow enclosure body closed at the top and open at the bottom adapted to be secured to the upper end of a housing and adapted to accommodate a water supply line and a water return line in spaced relation to the walls of the enclosure body, said enclosure body having an opening in a front wall adjacent the top to accommodate a hydrant valve attached thereto, said valve having a spout and an operating handle extending outwardly of the enclosure body and a valve body extending inside the enclosure body for attachment to the water supply and return lines, the enclosure body containing a second opening opposite the hydrant support opening and communicating with the interior of the enclosure body for introducing thermal insulation into the enclosure body, a removable plug closing the second opening, thermal insulation packed in said enclosure body surrounding the valve body and the water supply and return lines for protection against freezing, a hollow cover for the spout and operating handle, pivot supports for said cover on opposite sides of the enclosure body, an outwardly extending flange on said enclosure body disposed about the opening for said hydrant, and a flange on said cover adapted to overlie and cooperate with the flange on said body when closed to divert surface water from the hydrant spout, said cover swinging on said pivot supports between an open position in which the spout and operating handle are exposed and a closed position in which the cover shrouds the spout and operating handle.

5. A hydrant enclosure for a non-freezing pedestal-type hydrant which comprises a hollow enclosure body closed at the top and open at the bottom adapted to be secured to the upper end of a housing and adapted to accommodate a water supply line and a water return line in spaced relation to walls of the enclosure body, said enclosure body having an opening in a front wall adjacent the top to accommodate a hydrant valve attached thereto, said valve having a spout and an operating handle extending outwardly of the enclosure body and a valve body extending inside the enclosure body for attachment to the water supply and return lines, a hollow cover for the spout and operating handle, pivot supports for said cover on opposite sides of the enclosure body, an outwardly extending flange on said enclosure body disposed about the opening for said hydrant, the flange on the enclosure body including an upper portion which extends upwardly and forwardly from the enclosure body, the top of the enclosure body having a downwardly and forwardly extending portion which intersects the upper portion of the flange to form a V-shaped trough, and a flange on said cover adapted to overlie and cooperate with the upper portion of the flange on said body when closed to divert water on the top of the enclosure body from the hydrant spout, said cover swinging on said pivot supports between an open position in which the spout and operating handle are exposed and a closed position in which the cover shrouds the spout and operating handle.

6. A hydrant enclosure for a non-freezing pedestal-type hydrant which comprises a hollow enclosure body closed at the top and open at the bottom adapted to be secured to the upper end of a housing and adapted to accommodate a

water supply line and a water return line in spaced relation to the walls of said enclosure body, said enclosure body having an opening in a front wall adjacent the top to accommodate a hydrant valve attached thereto, said valve having a spout and an operating handle extending outwardly of the enclosure body and a valve body extending inside the enclosure body for attachment to the water supply and return lines, a hollow cover for the spout and operating handle, pivot supports for said cover on opposite sides of the enclosure body, outwardly extending side, top, and bottom flanges on said enclosure body disposed about the opening for said hydrant, said cover having side walls adapted to fit over the enclosure body side flanges when the cover is closed, a top flange on said cover adapted to overlie the top flange of the enclosure body when the cover is closed, a pair of sloping shoulders on said enclosure body extending backwardly and downwardly from the enclosure body top flange toward the pivot supports, side flanges on the side walls of the cover adapted to overlie the shoulders on the enclosure body when the cover is closed, and a stop attached to the enclosure body and adapted to limit swinging of said cover upon said pivot supports so that the cover at all times tends to fall to closed position under the influence of gravity, said cover swinging upon said pivot supports between an open position in which the spout and operating handle are exposed and a closed position in which the cover shrouds the spout and operating handle and the flanges provide an interlocking closure above the spout and operating handle.

7. A hydrant enclosure for a non-freezing pedestal-type hydrant which comprises a hollow hydrant enclosure body closed at the top and having an opening in a front wall adjacent the top to accommodate a hydrant valve attached thereto, side, top, and bottom flanges on said front wall about the opening, said hydrant valve having a spout and an operating handle extending outwardly of the enclosure body, a hollow cover for the spout and operating handle, pivot supports for said cover on opposite sides of the enclosure body, said cover having a top wall, a front wall, and a pair of side walls, a flange along said top wall and adapted to overlie the top flange of the enclosure body when the cover is closed, side walls of the cover being adapted to fit about the side flanges of the enclosure body when the cover is closed, a pair of shoulders on said enclosure body sloping downwardly and backwardly from the enclosure body top flange toward the pivot supports on opposite sides of the enclosure body, flanges along top edges of the cover side walls adapted to overlie the shoulders when the cover is closed, said cover front wall having a lower margin adapted to abut the body bottom flange when the cover is closed, said cover swinging upon said pivot supports between an open position in which the spout and operating handle are exposed and a closed position in which the cover shrouds the spout and operating handle, and a pair of inwardly extending flanges on the cover extending from the side walls and the lower margin of the cover adapted to abut the side flanges of the enclosure body when the cover is closed whereby an overlapping closure is formed between side walls of the cover and side flanges of the enclosure body.

AMOS O. PAYNE.
